UNITED STATES PATENT OFFICE

SETH R. CAMPBELL, OF BROOKES MILLS, PENNSYLVANIA

SURFACING MACHINE

Application filed February 13, 1930. Serial No. 428,112.

This invention, while relating generally to surfacing machines, has particular application to rotary lapping machines of the type shown in U. S. Letters Patent to Wyllis H. 5 Markland, No. 1,515,743, issued November 18, 1924. The invention may be adapted to a variety of uses, but its objects and advantages may be conveniently described with reference to its application to the particular 10 type of machine mentioned. Such machines are characterized by a rotating surfacing or grinding plate, and a surrounding carrier in the form of an annulus eccentric to the grinding plate and adapted to be rotated in 15 the opposite direction therefrom. Parts to be ground are held with their flat faces in contact with the grinding plate by means of a work-holder supported by and adapted to rotate with the surrounding annulus. 20 Machines of this type are commonly used for reconditioning or lapping small valves, such as the moving parts of triple valves, universal valves, distributing valves, and the like.

The object of the present invention is to 25 increase the capacity and the efficiency of such machines, and to this end I accomplish by the provision of means which enable the continuous operation of the machine over a comparatively long time without the necessity 30 of resurfacing the grinding plate. Heretofore it has been characteristic of such machines that the several articles being ground travel over a variety of overlapping courses on the grinding plate, by reason of the eccentric relation of the grinding plate and work-holder, but each article of work repeats its own course, so that the wear on the grinding plate, while somewhat distributed over its surfaces, is nevertheless non-uniform. 35 Accordingly the grinding plates have to be resurfaced quite frequently, and this is a factor tending to limit materially the capacity of such machines.

On the other hand, the present invention is 40 characterized by a relation between work-

holder and grinding plate which permits each article of work to travel over a different course on the grinding plate at each rotation so that a particular point on one item of work will describe an infinite number of courses 50 without repetition. Furthermore, the work may be so distributed that these courses will cover the entire surface of the grinding plate, with the result that there is a substantially uniform wear on the grinding plate, thus eliminating the necessity of truing the surface of the plate, save after a long period of 55 operation.

Other objects and advantages attained by 60 my invention will be apparent from the detailed description, which follows hereinafter, of one form which the invention may take. The description has reference to the embodiment of the invention illustrated in the accompanying drawings, of which:

Fig. I is a top plan view of a rotary lapping machine of my invention with one work-holding tray in position and the other removed, certain parts being broken away for clearness in illustration.

Fig. II is a side elevation of the upper part 70 of the same with a portion of the grinding plate and its surrounding annulus shown in cross-section.

Fig. III is a cross-sectional view of the 75 machine of Fig. I taken along the lines III—III of Fig. I; and,

Fig. IV is a detailed cross-sectional view 80 of the brake mechanism shown in Fig. III.

The machine shown is a rotary lapping machine comprising generally a rotary grinding plate 1, a surrounding carrier 2 in the form of an annulus or bowl eccentric to the grinding plate, and mechanism for causing the grinding plate to rotate in one direction and 85 the bowl in a reverse direction, the grinding plate in the instance shown being adapted to rotate at a speed five times greater than that of the bowl.

The mechanism for driving the grinding 90

plate 1 and the annulus or bowl 2 is similar to that shown in the above mentioned Letters Patent of Wyllis H. Markland and forms no part of this invention. Briefly it comprises a frame 3, which may conveniently be a part of a table or work bench, and a number of shafts and gears for transmitting power applied at the pulley 4 to the grinding plate shaft 5 and to the gear ring 6 on the annulus 2. The grinding plate shaft 5 is driven by a pulley shaft 7 through bevel gears 8 and 9. An additional gear 10 on the grinding plate shaft 5 engages an idler 11 which in turn drives a pinion 12 on a shaft 13. The shaft 13 through an additional pinion 14 drives the annulus 2, the pinion 14 engaging the gear ring 6 on the underside of the annulus 2, causing the same to rotate about the eccentric hub 15 on the frame 3. On the grinding plate shaft 5 is a driving plate 16 provided with a screw 17 near its perimeter. The screw 17 is adapted to engage one of a set of similar screws 18 used for levelling the grinding plate. This furnishes a positive drive, while permitting the grinding plate to be easily removed. Suitable arrangement, which need not be here described, is made for oiling the various shaft bearings.

The mechanism thus far described effects the opposite rotation at a predetermined speed ratio, say five to one, of the grinding plate 1 and the surrounding eccentric annulus 2.

Centrally of the grinding plate 1 there is an annular recess 19 designed to accommodate a floating plate 20. This plate 20 has merely a frictional engagement with the grinding plate 1 so that it will float on the grinding plate unless otherwise restrained. A disc 21 is internally threaded to engage corresponding threads on the floating plate 20, and a set screw 22 is provided to enable an adjustment between the disc 21 and floating plate 20 for reasons hereinafter pointed out, these parts being held in fixed relation by the set screw 22 while the machine is in operation. The floating plate 20 and the superimposed disc 21 together constitute a work-holder support.

Eccentrically mounted on the disc 21 are a threaded pin 23 and a ball race 24, these parts serving as a bearing for the work-holder or carrier 25. The pin 23, though off center from the grinding plate 1, is centered with respect to the annulus or bowl 2, when the parts are in the position shown in the drawings. The work-holder 25 is always eccentric to the grinding plate 1 and at times concentric with the annulus or bowl 2. A cap 26 engages the upper threads of the pin 23 and serves to hold the work-holder 25 in place, while permitting its ready removal. The cap 26 is recessed at 27 so that it does not come in frictional contact with the work-holder 25.

The work-holder 25 comprises a spider frame adapted to accommodate in its semi-circular openings 28 removable trays 29 which carry the work to be ground. The trays 29 are provided with openings 30 of a size to accommodate the particular type of work. I preferably employ a series of such trays with openings of a variety of shapes suiting the parts which are customarily resurfaced on the machine. The trays 29 are retained within the work-holder 25 by flexible metal straps 31 having slots 32 engaging pins 33 on the work-holder which permit a limited sliding movement of the straps around the work-holder. The straps 31 are provided with lugs 34 forming additional slots 35 which are adapted to engage and disengage projections 36 on the trays 29. Tension springs 37 with one end attached to a strap 31 and the other attached to the work-holder 25 tend to rotate the straps 31 to the position shown at the left hand of Fig. I, in which position the trays 29 may be lifted from the work-holder 25. The straps are also provided with finger grips 38. By pressing the finger grips 38 together the straps will be rotated against the pressure of the springs 37 about the work-holder 25 and the tray projections 36 will be caught in the slots 35 as shown at the right-hand of Fig. II. The straps 31 when so moved are automatically locked by pins 39 on the spring pressed angle members 40, the pins 39 fitting in corresponding holes 41 in the work-holder 25. To release the straps 31 the angle members 40 are pressed against the springs 42 releasing the pins 39 from the holes 41 and permitting the tension springs 37 to return the straps 31 to their original position.

The work-holder 25 has an arm 43 affixed thereto by screws 44. The arm 43 is slotted at 45 and adapted to move with a reciprocatory motion about a pin 46 with a knurled knob 47 and lower threaded portion engaging the head of a screw 48. This screw 48 in turn fits in a threaded opening in the rim of the annulus 2. It may be turned to adjust the level of the surface upon which the arm 43 bears. By this adjustment and the further adjustment afforded by the threaded floating plate 20 turning within the disc 21, all the parts may be levelled and vertically aligned to compensate for a change in thickness of the grinding plate 1 or wear on the contacting surfaces of other moving parts.

Housed within the work-holder 25 is a brake mechanism comprising a brake rod 49 carrying a brake shoe 50 adapted to engage and disengage the floating disc 21. The brake rod 49 has a threaded end 51 fitting a correspondingly threaded opening in an arm 52 which is adapted to slide back and forth within the cavity 53. The brake shoe 50 is pivoted at 54 on the brake rod 49 and the shoe is normally held apart from the disc 21

by means of a spring 55 which forces the arm 52 outward until its shoulder 56 strikes a stop 57 on the work-holder 25.

It will be apparent from the description thus far that the rotary movement of the grinding plate 1 will cause a similar movement of the floating plate 20 and disc 21 which will effect a rotation of the axis of the work-holder 25. The work-holder 25 being connected by the arm 43 to the annulus 2 will, of course, make one revolution for every revolution of the annulus, but its center will at the same time make five revolutions about the center of the grinding plate 1, causing a reciprocatory movement of the arm 43 with five double strokes for each revolution of the annulus. During four double strokes of the arm 43, the brake arm 52 will not strike the rim of the annulus 2 on account of the space between the grinding plate 1 and annulus 2 being sufficiently wide to permit the brake arm 52 to travel back and forth with the work-holder arm 43, but at one point in the operation of the machine (when the elements are in the position shown in the drawings), the space between the grinding plate 1 and annulus 2 is so restricted that the brake arm 52 in passing will strike the annulus and be moved inward a short distance, thus applying the brake shoe 50 to the floating disc 21 for an instant. When the brake mechanism is operated the floating plate 20 and disc 21 will be restrained from rotating with the grinding plate 1, and will be subjected to the rotary movement of the annulus 2. Accordingly, the axis of rotation of the work-holder will remain stationary for an instant with respect to the annulus 2. This will effect a change in the angle $a b c$ between a point on the grinding plate, the center of the grinding plate, and the axis of rotation of the work-holder, which in turn will effect a change in the course which a point of the face of an article being ground will describe on the grinding plate.

To adjust the operation of the brake, I provide a set screw 58 so that the total length of the brake rod 49 and brake arm 52 may be varied and set at the desired measure.

The hub portion 59 of the work-holder 25, except for the instant at which the brake is applied, rotates in the opposite direction from that of the disc 21. To provide a wearing surface on the disc 21 I form the disc with a raised portion 60 in the form of a circular track eccentric to the disc 21 but concentric with the hub 59.

The operation of the machine will be apparent from the description of its constituent elements. If the brake mechanism were not employed, the path of each article of work would constitute a definite cycle distributed over the face of the grinding plate, but repeating itself. However, each time the annulus 2 completes a revolution, the application of the brake changes the angle between

a point on the grinding plate, the center of the grinding plate and the axis of rotation of the work-holder, so that a new path or course is described. Theoretically a circle may be divided into an infinite number of degrees and fractions thereof so that the machine may be accurately described as operating upon a principle permitting the work to describe an infinite number of courses over the grinding plate. As a practical matter there is, of course, a limitation on the operation without repetition (the period of application of the brake mechanism cannot be reduced beyond a certain point); but this limitation does not effect the practical operation of machines embodying my invention, because a repetition of the course described by a point on the work being ground, if it does occur, will occur so infrequently that the grinding plate will wear uniformly throughout, this wear being distributed over its entire surface.

The automatic changing of the relative positions of the axes of work-holder and grinding plate, resulting as it does in the uniform wearing of the surface of the grinding plate, renders it commercially practicable to increase the capacities of machines of this type and affords other advantages which will be manifest to those skilled in this art.

While my invention has been described in some detail with respect to a specific embodiment thereof, it will, of course, be apparent that various changes may be made in the particular form here illustrated and described without departing from the spirit of the invention, as claimed.

Having thus described my invention, I claim:

1. A surface grinding machine including a rotary grinding plate, a surrounding annulus eccentric to said grinding plate and adapted to be rotated in the opposite direction therefrom, a work-holder supported on a bearing frictionally engaging said grinding plate, an arm connecting said work-holder and the annulus aforesaid whereby the work-holder is adapted to rotate with said annulus, and means whereby said bearing is at times subjected to the rotary movement of the grinding plate and at times subjected to the rotary movement of said annulus.

2. A surface grinding machine including a rotary grinding plate, a surrounding annulus eccentric to said grinding plate and adapted for opposite rotation, a floating plate frictionally engaging said grinding plate, a bearing eccentrically mounted on said floating plate, a work-holder on said bearing adapted to rotate with the said annulus, and means whereby said floating plate is at times subjected to the rotary movement of said grinding plate and at times subjected to the rotary movement of said annulus.

3. A surface grinding machine including a

5 rotary grinding plate, a surrounding annulus eccentric to said grinding plate and adapted for opposite rotation, a floating plate frictionally engaging said grinding plate, a bearing eccentrically mounted on said floating plate, a work-holder on said bearing and adapted to rotate with said annulus, and a brake adapted to engage intermittently said floating plate to subject the same to the rotary movement of 10 said annulus.

10 4. A surface grinding machine including a rotary grinding plate, a surrounding annulus eccentric to said grinding plate and adapted for opposite rotation, a floating plate frictionally engaging said grinding plate, a bearing eccentrically mounted on said floating plate, a work-holder on said bearing adapted to rotate with said annulus, a brake normally separated from said floating plate, and a reciprocal arm for causing said brake upon each revolution of the annulus to bear upon the said floating plate for an instant to subject the same to the rotary movement of said annulus.

15 25 5. A surface grinding machine including a rotary grinding plate, a surrounding annulus eccentric to said grinding plate and adapted for opposite rotation, a floating plate frictionally engaging said grinding plate, a bearing eccentrically mounted on said floating plate, a work-holder on said bearing adapted to rotate with said annulus, and means for adjusting the vertical position of said bearing with respect to said floating plate.

20 30 35 40 45 6. A surface grinding machine including a rotary grinding plate, a surrounding annulus eccentric to said grinding plate and adapted for opposite rotation, a pin on said annulus, a work-holder having a central bearing rotating with said grinding plate, the axis of said work-holder being eccentric to the axis of said grinding plate, and a slotted arm engaging the pin on said annulus whereby said work-holder is adapted for relative reciprocatory and rotary movement with respect to said grinding plate.

45 50 55 60 7. A surface grinding machine comprising a carrier, a grinding plate rotatable with respect to said carrier, a work-holder eccentric to the grinding plate and engaged by said carrier, a work-holder support normally subject to the rotation of said grinding plate, and means periodically acting upon said work-holder support to connect said support with said carrier so that said support ceases to rotate with said grinding plate, thereby effecting a change in the relative positions of the axes of said grinding plate and work-holder.

65 65 8. A surface grinding machine comprising a carrier, a grinding plate rotatable with respect to said carrier, a work-holder eccentric to the grinding plate and engaged by said carrier, a work-holder support normally sub-

ject to the rotation of said grinding plate through frictional engagement therewith, and means periodically engaging said work-holder support and connecting the same with said carrier so that said support ceases to rotate with said grinding plate, thereby effecting a change in the relative positions of the axes of said grinding plate and work-holder.

70 75 In testimony whereof, I have hereunto signed my name at Altoona, Pennsylvania, this 4th day of February, 1930.

80 SETH R. CAMPBELL.
